Howson and Howson

UNITED STATES PATENT OFFICE

ALBERT E. PAGE, OF BROOKLYN, NEW YORK, ASSIGNOR TO SCOTT & WILLIAMS, INCORPORATED, OF NEW YORK, N. Y., A CORPORATION OF MASSACHUSETTS

KNITTED FABRIC

Application filed March 25, 1932. Serial No. 601,804.

This invention relates to weft knitted fabrics, i. e., fabrics knit in the direction of the courses, and more particularly to picot edges for the welts of stockings. One object of the invention is to produce a good picot edge by means of a special float stitch. According to this invention, the picot edge is made of two yarns, the peaks being formed by an aggregation of loops and the valleys 10 being formed by floating one of the two yarns.

In the drawing,

Figure 1 is an outline of a stocking showing the location of the picot edge thereon; 15 Figure 2 is a diagrammatic picture of the face of fabric made in accordance with the invention, showing the intermeshing of the loops at the picot edge, all the stitches of certain wales being knit of both yarns; while 20 Figure 3 is a similar diagrammatic showing of the intermeshing of the loops at the picot edge in the preferred form of the invention where there are float loops in each wale.

The invention will be shown and described embodied in a stocking having an inturned welt, knit on the well-known Scott & Williams independent needle type of hosiery machine. A machine for making an automatic inturned welt is shown and described in the patent to Robert W. Scott No. 1,282,958, dated October 29, 1918. As already mentioned, this invention relates to a weft knit stocking, that is to say, one in which the knitting proceeds in the direction of the courses, and more particularly to such a stocking when knit on a machine in which the needles knock over their stitches in succession rather than simultaneously. A picot edge made in accordance with this invention is knit of two yarns, one yarn preferably being heavier than the other. Thus, for instance, one yarn may be 100 denier and the other yarn 50 denier. It is the heavier yarn which is floated if the yarns are of an unequal weight. Usually the entire welt is made of the same yarns that are used in knitting the picot edge.

Referring now to the form of the invention shown in Figure 2, it will be noted that the

picot edge is composed of a special form of "half float" construction, by which is meant a construction in which one of the yarns is floated in certain wales while the other wales are knit with both yarns. The patent to E. A. Hirner No. 1,082,910, dated May 27, 1913, describes one form of half float fabric and of how the fabric may be obtained. In the particular form of this half float fabric shown in Figure 2, the machine in knitting from the beginning of the welt up to the fold has been knitting regular plated courses 10 in all of the wales. The lower edge 12 of the fabric shown in this figure was knit first, the knitting progressing from the lower edge 12 to the upper edge 13 of the figure. When the knitting reaches the fold or top of the welt, a limited number of special courses 14, 15 are inserted, in which the heavier or facing yarn forms floats 18 in recurrent wales in order to produce a picot effect 11. In the needle wales 16 each stitch which is formed only from the lighter yarn 17 is floated by the heavier yarn. The other wales 21 are made of regular plated stitches. It is preferable in this form of the invention to make only about two courses 14, 15 in this manner, and that is the number of special courses shown in Figure 2. These special courses are immediately followed by plated courses so that in the wales where the half float stitches occur, those half float stitches are immediately followed by stitches knit with both yarns. By thus floating one yarn in these picot courses 14, 15 in certain wales 16 and making the stitches in the adjacent wales 21 of both yarns, and intermeshing the special stitches in the second course 15 by stitches knit of both yarns, a picot effect is obtained when the fabric is folded. The diagonal effect given this picot can be seen in Figure 2, the line of the fold being indicated by the dot-and-dash line $\text{---} \text{---}$. The fabric shows a marked tendency to fold along the line $\text{---} \text{---}$ —presumably because of the total absence of floats of the heavy yarn at the line.

The preferred form of construction is that shown in Figure 3, the special courses being similar to those shown in the patent to Fred W. Smith No. 1,772,230, dated August 5, 1930.

The fabric is knit from the lower edge 12 to the upper edge 13, as in Figure 2.

This preferred form of construction involves varying the wales in which the half floats occur, the particular form shown in Figure 3 being one in which there are these half float stitches in each wale. In this form of the invention half float stitches are made in one group of recurrent wales for one or 10 more courses and then plain plated stitches are made in those wales, while the other recurrent wales which theretofore had been making plain plated stitches begin to make half float stitches for one or more wales. In 15 the illustration of the invention shown in Figure 3, there are four special courses 22, 23, 24, 25 used in making the picot edge 11, the first two courses 22, 23 containing half float stitches in alternate wales 26, immediately 20 followed by two courses 24, 25 containing half float stitches in the intervening wales 27. It has been found that by making four special courses alternated in the manner described, a diamond-shaped structure results, 25 giving a particularly good picot edge appearance to the stocking, the loops being drawn to peaks 28 with only long bights 29 of the lighter yarn 17 therebetween. It has been noted that in this form of the invention 30 the fold occurs along the dot-and-dash line y—y, that is to say, approximately between the second special course 23, i. e., the last course knit on the first group of wales 26 to have the special half float stitch, and the first 35 of the two courses 24, 25 having the special half float stitch on the other wales 27. It has been found that this form of structure has a pronounced tendency to "break" or bend along this line, the tendency being more pronounced than in the structure shown in Figure 2. In making this fabric, the mechanism shown and described in the above-mentioned patent to Fred W. Smith No. 1,772,280 can be employed, the construction there being 40 one in which pattern jacks are employed to raise alternate needles to a level where they will take both yarns, the non-selected needles taking only one yarn. This arrangement also permits shifting the floats to the other wales, 45 when that is desired. The facing yarn may be the one that is floated, and in this case the facing yarn will be the heavier yarn if a difference in weight of yarn is used.

It will be observed in the construction 50 shown in Figure 3 that the sinker wales 30 on each side of the fold come approximately behind each other and provide a peak 28 or taper, thus making a good-looking picot edge. This is partly due to the fact that the wide 55 points of the diamond-shaped formation in the wales 26 first knit with the half float stitch, i. e., the half float stitches nearest the lower edge 12 of Figure 3, are directly followed by plain plated stitches in courses 60 24, 25, 31 which tend to reduce the distortion 65 of those half float stitches.

Stated another way, the diamond formation, generally speaking, is caused in the same manner in which the diamond formations are caused in the above-mentioned patent to Fred W. Smith No. 1,772,280, and the coincidence of the peaks on the inside and the outside of the fold in the form of the invention shown in Figure 3 is due largely to the juxtaposition of the course composed entirely of plain plated stitches with the course containing the slackest stitches in one of the two recurrent groups of wales.

What I claim is:

1. A woft knit stocking having a folded 80 welt with a picot formation made of two yarns at the upper edge of said folded welt, said formation comprising recurrent wales having one yarn floated at the picot formation, the stitches in the adjacent wales in the same course and the stitch in the same wale in an adjacent course each being knit of two 85 yarns.

2. A woft knit stocking having a folded 90 welt with a picot edge at said fold and a plurality of courses formed of two yarns, one heavier than the other, the heavier yarn being floated in recurrent wales in a plurality of said courses, and the stitch in the adjacent wale in one of said courses being knit of 95 two yarns.

3. A woft knit stocking having a folded 100 welt with a picot formation at the fold of said welt composed of a plurality of courses knit of two yarns of unequal weight, the 105 heavier of said yarns being floated in recurrent wales in one or more of said picot edge courses and a plain plated course adjacent thereto to produce a diamond-shaped structure in the wales containing said half float 110 stitches.

4. A seamless stocking having a folded 115 welt with a picot edge formation at the fold of said welt composed of a plurality of courses knit of a plurality of yarns of unequal weight, one of the heavier of said yarns being floated in all of said wales in said picot 120 edge, the floating occurring on recurrent wales in one or more successive courses and in the intervening wales in the remaining picot edge courses and the fold occurring 125 where the half float stitches are staggered, to produce diamond formations pointing in opposite directions in adjacent wales to make the peaks and valleys of said picot edge.

5. A seamless stocking having a folded 130 welt with a picot edge formation at the fold of said welt composed of a plurality of courses knit of a plurality of yarns of unequal weight, one of the heavier of said yarns being floated in all of said wales in said picot edge, the floating occurring on recurrent wales in one or more successive courses and in the intervening wales in the remaining picot edge courses and the fold occurring 135

where the stagger in the half float stitches occurs, to produce diamond formations pointing in opposite directions to make the peaks and valleys of said picot edge, the 5 course on each side containing half float stitches furthest from the fold being adjacent to a course containing plain plated stitches.

6. A weft knit stocking having a folded 10 welt with a picot edge formation at the upper edge of said welt, said formation being composed of a plurality of courses each having a plurality of yarns including one yarn heavier than another, the heavier yarn being 15 floated in recurrent wales in a plurality of said courses and the stitch in the adjacent wale in one of said courses being knit of all the yarns.

7. A weft knit stocking having a picot 20 edge formation in the welt, said formation being composed of a plurality of courses each having a plurality of yarns of different weights, a heavier yarn being floated in recurrent wales in a plurality of said courses 25 and the stitch in the adjacent wale in one of said courses being knit without floats, the welt being folded along a line having no floats of said heavier yarn, certain stitches at said line lacking said heavier yarn.

80 In testimony whereof I have signed my name to this specification.
